UNITED STATES PATENT OFFICE

ARTHUR SCHURIG, OF SAARBRUCKEN, GERMANY, ASSIGNOR TO GESELLSCHAFT FÜR FORDERAULAGEN ERNST HECKEL MIT BESCHRANKTER HAFTUNG, OF SAARBRUCKEN, GERMANY

DRIVING PULLEY FOR ROPES OR CHAINS PROVIDED WITH GRIPPING JAWS

Application filed July 11, 1929, Serial No. 377,543, and in Germany February 1, 1929.

Driving pulleys for ropes or chains, provided with gripping jaws as at present constructed can be used only for low speeds for the reason that the tremendous centrifugal force which is generated at the higher speeds throws the gripping jaws outwards with great force into their position of rest, so that at first a loud rattling noise is produced; furthermore the gripping jaws do not open quickly enough, so that they are ejected from the pulley without engaging in the notches which form their position of rest. Another disadvantage is that the heavy blows of the gripping jaws prematurely wear away the material.

To overcome these disadvantages the gripping jaws are provided according to the invention with a buffer device.

This buffer device may consist of a known type of buffer operated by air, a liquid or a spring or by any other elastic material; the buffer action may also be produced by the combination of several of the elements mentioned. It is advantageous for the buffer to act radially and for one buffer element to be secured on the pivot bolt of the gripping jaws and the other on the rim of the driving pulley.

It is proposed to make one or both buffer elements regulable in known manner by a set screw or some similar device so that the buffers come into action only when the gripping jaws are in a particular position. In order to keep the cross-section of the rim of the driving pulley as small as possible, it is advantageous to provide the buffer apparatus outside the rim of the wheel and turned towards the hub. In this case the buffer apparatus may be enclosed in known manner in a protective casing so as to protect it from dirt and the like.

The device according to the invention is diagrammatically illustrated by way of example in the accompanying drawings, the construction selected being one in which an air buffer apparatus is provided within the rim of the driving pulley.

Figure 1 shows the gripping jaws in the operative position, that is to say in the condition in which they are forced inwardly, and

therefore together, by the radial, inwardly acting pressure of the rope.

Figure 2 shows the gripping jaws at the moment at which the rope runs off the pulley, the gripping jaws are wide open and the buffer apparatus is coming into action.

In the drawings, 1 denotes the rim of the driving pulley and 2 a pair of gripping jaws; 3 is the buffer apparatus, and 4 the rope. The air cylinder 5 of the buffer apparatus 3 is connected to the pivot bolt 7 of the gripping jaws 2 by means of two arms 6, while the piston 8 is secured to the rim 1 by means of the rod 9 and the check nut 10.

The buffer apparatus operates as follows: When the rope runs off, the gripping jaws are opened by the spring 11, the cylinder 5 moving radially outwards under the additional action of centrifugal force. The air compressed by the piston 8 escapes through the holes 12 until, after they have been masked, the air buffer 13 comes into operation, whereby a gentle braking action is exerted on the gripping jaws. The buffer apparatus can be so adjusted by the check nut 10 that it comes into action only when the gripping jaws are in a particular position. By specially arranging the holes 12 the action of the buffer can be accurately determined. This is also possible when springs 80 are used, inasmuch as they can be telescoped into each other for example to different lengths.

Another advantage secured by the use of the apparatus according to the invention is that the projection 14, which in the known types of apparatus hold the gripping jaws securely in the rim of the driving pulley are now superfluous.

I claim:—

1. Driving pulleys for flexible elements, such as ropes, provided with gripping jaws mounted in the rim of the pulley capable of movement in the radial direction relatively to the axis for the purpose of engaging and releasing the flexible element, and buffer apparatus mounted upon the said pulley and operating upon the gripping jaws to brake and limit the outward movement thereof.

2. Driving pulleys for flexible elements, such as ropes, provided with gripping jaws mounted in the rim of the pulley capable of movement in the radial direction relatively to the axis for the purpose of engaging and releasing the flexible element, and pneumatic buffer apparatus mounted upon the said pulley and operating upon the gripping jaws to brake and limit the outward movement there-
10 of. 75
3. Driving pulleys for flexible elements, such as ropes, provided with gripping jaws mounted in the rim of the pulley capable of movement in the radial direction relatively to the axis for the purpose of engaging and releasing the flexible element, and hydraulic buffer apparatus mounted upon the said pulley and operating upon the gripping jaws to brake and limit the outward movement there-
15 of. 80
4. Driving pulleys according to claim 1, provided with buffer devices connected to the gripping jaws on the inner side and disposed to act in the radial direction relatively to the axis of the pulley. 85
5. Driving pulleys according to claim 1, provided with buffer devices comprising two relatively moving elements, and means for constraining the relative movement, one of the said elements being connected to the corresponding gripping jaws and the other to the rim of the driving pulley. 95
6. Driving pulleys according to claim 1, provided with buffer devices comprising relatively movable elements, means for constraining the relative movement of the said elements, and an adjustable connection between one of the said elements and the part of the pulley with which it is connected. 100
- 40 7. Driving pulleys according to claim 1, provided with buffer devices comprising piston and cylinder elements, one of which elements is connected to the corresponding gripping jaws and the other of which elements is connected to the rim of the pulley. 105
- 50 8. Driving pulleys according to claim 1, provided with buffer devices comprising piston and cylinder elements, one of which elements is connected to the corresponding gripping jaws and the other of which elements is connected to the rim of the pulley, and means for adjusting one of the said connections so that the buffer comes into action only when the gripping jaws are in a determined position. 110
- 55 9. Driving pulleys according to claim 1, provided with buffer devices comprising two relatively movable elements and means for constraining the said relative movement, the said buffer devices being disposed between the gripping jaws and the pulley rim on the inner side of the said rim. 115
- 60 10. Driving pulleys according to claim 1, provided with buffer devices connected be- 120
- 65 tween the gripping jaws and the pulley rim, the said buffer devices being on the inner side of the said rim, and a cover enclosing the said buffer devices. 125
